CLAIM

The ornamental design for a wrist-mounted toy lion head, substantially as shown and described.

DESCRIPTION

FIG. 1 is a front elevational view of a wrist-mounted toy lion head showing my new design;

FIG. 2 is a left-side elevational view thereof, the right side being substantially a mirror image thereof; and

FIG. 3 is a rear elevational view thereof.

FIG. 1

FIG. 3
